UNITED STATES PATENT OFFICE.

JAMES W. KEATING, OF PORTLAND, OREGON,

SWITCH-OPERATING MECHANISM.

No. 891,427.

Specification of Letters Patent.

Patented June 23, 1908.

Application filed August 28, 1907. Serial No. 390,515.

To all whom it may concern:

Be it known that I, JAMES W. KEATING, a citizen of the United States, residing at Portland, in the county of Multnomah and State 5 of Oregon, have invented a new and useful Improvement in Switch-Operating Mechanism, of which the following is a specification.

This invention relates to switch operating mechanisms, the object being to provide 10 very novel and efficient means for locking the switch points in an opened or closed position automatically, so that all danger of the switch points being moved accidentally, is prevented.

Another object of my invention is to provide very novel point operating mechanism 15 so constructed that the locking levers will be released before the points start to move, so that all danger of the locking levers being 20 broken when operating the switch is prevented.

With these and other objects in view, the invention consists in the novel features of construction, combination and arrangement 25 of parts, hereinafter fully described and pointed out in the claims.

In the drawing forming part of this specification:—Figure 1 is a side elevational view of my improved switch operating mechanism 30 in a closed position, the rails and switch points being shown in section. Fig. 2 is a side elevational view of the operating mechanism in an opened position, the rails and switch points also being shown in section. 35 Fig. 3 is a top plan view of a portion of the main track and siding showing my improved switch operating mechanism in place.

Referring to the drawing A indicates the main track, B the siding and C the pivoted 40 switch points connecting the same, which are connected together by spaced bars C'.

The bases of the points are connected together adjacent their free ends by a bar D which is provided with a central depending 45 U-shaped portion D', the vertical walls of which are apertured in alinement with each other, through which extends the ends of the switch operating rod E which is provided with a turn-buckle E', so that it can be adjusted, and is connected to the usual switch- 50 stand, (not shown). An inverted V-shaped lug E² is formed on the rod E in the U-shaped portion of the bar D forming a stop which is adapted to engage the sides of the

U-shaped portion for operating the switch- 55 points.

Secured on the top of the adjacent tie between the points, are plates F and G provided with outwardly projecting pins F', G', on which are pivotally mounted locking levers H and I, which are provided with spaced lugs H', H², I', I², at their outer ends adapted to fit up beside the bases of the rails and points and secure the points against the rail when forced together as will be hereinafter 60 fully described. The inner ends of the levers are provided with enlarged offset members H³, I³ forming weights which normally hold the lever in a horizontal position. The under side of the members are provided with 65 beveled faces H⁴, I⁴ adapted to slide on the V-shaped lug E² of the operating rod E when the rod is operated, so that the member will be lifted out of the U-shaped portion of the 70 bar and release the switch-points, so that 75 they can move.

The operation is as follows:—When the switch is in a closed position, as shown in Fig. 1, and the switch-rod is pushed, the inverted V-shaped portion of the rod E will 80 force the offset member I³ of the rod I up out of the U-shaped portion of the bar and the other end provided with lugs down out of engagement with the rails and points and as the rod is forced further forward, the lug E² 85 will engage the wall of the U-shaped portion of the bar D and open the switch so that the train can pass into the siding. At the same time, the offset member H³ of the lever H will drop into the U-shaped portion of the 90 bar onto the V-shaped lug, and the lugs on the other end of the lever will be brought up along side of the bases of the rail and point, so as to securely lock the switch in an opened 95 position.

When it is desired to close the switch, the rod is drawn outwardly which releases the locking lever H, and allows the locking lever I to lock the switch in a closed position. To further lock the movable rails in position I 100 provide curved pivoted locking members I⁵ carried by the locking levers H and I and which when in closed position have one end in engagement with the flange or base of the switch point and the other end in engagement with the under face of the base of one of the track or switch rails. This prevents the 105 switch point from moving as long as the

locking members I^5 are held by the bar H or I in locking position, as pressure exerted by the switch point upon the end in engagement with the base of the point would cause the 5 opposite end of the member I^5 to grip tighter the base of the rail, A or B , thus the more firmly holding the member I^5 in such locking position.

Having thus fully described my invention, 10 what I claim as new and desire to secure by Letters Patent is:—

1. A switch operating mechanism including fixed rails and movable points, a bar extending between and connecting said points, 15 weighted locking levers between said points provided with lugs for engaging the rails and points, and a slidably arranged rod for operating said locking levers and moving said points.
2. In a switch operating mechanism, the combination with fixed rails and movable points, of a bar connecting said points provided with a **U**-shaped portion, weighted locking levers arranged between said points 25 provided with spaced lugs at one end adapted to fit beside the base of the rail and point, and a rod slidably mounted in said **U**-shaped portion for operating said points and said locking levers.
3. In a switch operating mechanism, the combination with fixed rails and movable points, of a bar connecting said points provided with a **U**-shaped portion, locking levers pivotally mounted between said points, 30 provided with weighted offset ends adapted to fit in said **U**-shaped portion of said bar, and an operating rod extending through said

U-shaped-portion provided with a lug adapted to engage said offset members, and said **U**-shaped portion, for the purpose described. 40

4. The combination with fixed rails and movable points, of a bar connecting said points provided with a depending **U**-shaped portion, the vertical walls of which are apertured in alinement with each other, locking 45 levers mounted between said points provided with offset members adapted to fit in said **U**-shaped portion of said bar, and a switch operating rod extending through the aperture of the **U**-shaped portion of the bar provided with an inverted **V**-shaped lug adapted to engage said offset members, and said **U**-shaped portion, for operating said locking levers and points. 50

5. In a switch operating mechanism, the 55 combination with fixed rails and movable points, of a bar connecting said points provided with a depending **U**-shaped portion, locking levers pivotally mounted between said points provided with spaced lugs at one 60 end, and offset members at the other ends, said offset members being provided with beveled underfaces a switch operating rod slidably mounted in said **U**-shaped portion provided with an inverted **V**-shaped lug 65 adapted to lift the offset members of the locking lever out of the **U**-shaped portion and release the points and operate said points.
